UNITED STATES PATENT OFFICE

93,259

DESIGN FOR A RADIO FIREPLACE

John Weible and Forrest Lohr, Stoyestown, Pa.

Application March 15, 1934, Serial No. 51,071

Term of patent 7 years

To all whom it may concern:

Be it known that we, JOHN WEIBLE and FORREST LOHR, citizens of the United States of America, residing at Stoyestown, in the county of Somerset and State of Pennsylvania, have invented a new, original, and ornamental Design for a Radio Fireplace, of which the following is a specification, reference being had to the accompanying drawing, forming a part hereof.

In the drawing:

The figure represents a perspective view of a radio fireplace showing our design.

The design consists of the fireplace proper, with the checkered tile extension, fire log, and-iron elements, and the three objects illustrated at the top of the fireplace, all formed integral with the fireplace proper as shown.

We claim:

The ornamental design for a radio fireplace, as shown and described.

JOHN WEIBLE [L. s.]
FORREST LOHR. [L. s.]
